Primary Examiner — Michael C Stout*Assistant Examiner* — Paul D Bohannon*(74) Attorney, Agent, or Firm* — Schroeder Law PC**(57) CLAIM**

The ornamental design for a chair, as shown and described.

DESCRIPTION

FIG. 1 is a front perspective view of a chair showing my new design;

FIG. 2 is a rear perspective view thereof;

FIG. 3 is a front elevation view thereof;

FIG. 4 is a rear elevation view thereof; and,

FIG. 5 is a right side elevation view thereof, the left side elevation view being a mirror image thereof.

The bottom view forms no part of the claimed design.
